WATER COOLER

Edward T. Williams, Pelham Manor, N. Y.

Application December 5, 1931, Serial No. 579,197

3 Claims. (Cl. 62—141)

This invention relates to water coolers and more particularly to a water cooler having mechanical means for reducing the temperature of water flowing from a city pressure supply line into the machine from which it is dispensed through a bubbler or other dispensing medium. One important object of the invention is to utilize the cold waste water for cooling the incoming water, and also for cooling the low pressure gas returned to the compressor.

Fig. 1 is a diagrammatic view illustrating one application of the invention;

Fig. 2, a fragmentary side elevation illustrating a different method of applying the waste water cooling coil around the motor dome;

Fig. 3, a top plan view of a different application than that of Fig. 2, the waste water cooling coil being applied flat around the exterior of the top of the dome; and

Fig. 4, a fragmentary vertical section of a further modification with the waste water cooling coil around the interior of the top of the dome.

Referring to Fig. 1 of the drawings, one arrangement in accordance with this invention comprises a motor compressor unit 10 having a dome or casing 11, a condenser 12, and an evaporator 23. Refrigerant vapor compressed by the motor compressor unit is discharged into the condenser 12, liquefied, and the liquid transferred through a capillary tube 22, or equivalent pressure reducing means, into the evaporating chamber 23 where it is vaporized, absorbing heat from the liquid contained within the inner shallow wall of such evaporating chamber. The vapor is then withdrawn by the compressor through suction line 24 to the interior of the dome or casing 11. This gas is of low pressure and of relatively high temperature, such temperature being increased by the absorption of heat from the motor compressing unit under the dome, the gas becoming superheated, thus decreasing the efficiency of the unit.

Water to be cooled is supplied from a supply line through pipe 14 to the interior of the cooling chamber 13 within the confines of the evaporator 23, and is discharged therefrom through pipe 15 and bubbler 16, the discharge being controlled by push button control valve 17.

In order to insure water withdrawn from the cooling chamber being thoroughly chilled a shell 25 is disposed within the cooling chamber and such shell forms with the inner wall of the evaporator a shallow chamber, communication between the interior and exterior of the shell or the shallow chamber and the interior of the shell

being established by means of a opening 26 near the top of the shell 25.

The inlet pipe 14 admits water to the interior of the shell 25, and the discharge pipe 15 removes water from the exterior of the shell or from the shallow chamber. With this construction, water coming in through the pipe 14 will be required to pass through the opening 26 and around to the discharge pipe 15 before it can pass out, thereby coming into good heat exchange relation with the evaporator.

Waste water from the bubbler 16 is collected in a drip basin 18. This cold waste water is discharged through a pipe 19 which forms with a chamber 20 disposed about the same and being interposed in the water inlet pipe 14, a heat exchanger by means of which heat from the incoming water is transferred to the waste water discharged through the pipe 19.

In order to reduce the temperature of the low pressure gas in the motor compressor dome, the pipe 19 is associated with such dome in a manner to form a second heat exchanger in order to transfer heat from such low pressure gas to the waste water. The manner of effecting this heat transfer from the low pressure gas to the waste water flowing through the pipe 19 is accomplished in either of the ways shown in Figs. 1, 2, 3, or 4, the illustration in Fig. 4 being preferable for the type of motor compressor unit shown. In Fig. 1 this result is accomplished by coiling the waste water pipe 19 around the motor compressor unit in the upper portion of the dome. In Fig. 2 the waste water coil 19 is around the exterior of the casing or dome in a manner to provide good thermal contact between the coil and the interior of the dome. In Fig. 3 is shown the simplest form for effecting the desired heat exchange relation. In this embodiment the waste water pipe 19 is coiled first upon the top of the dome, and since it is on the exterior of the dome it is preferably brazed or otherwise intimately secured to the dome.

The embodiment of Fig. 4 is similar to that of Fig. 3 except the waste water pipe 19 is coiled around the interior of the top of the casing or dome. It is unnecessary in this embodiment to join the coil intimately with the dome as the coils are directly exposed to the low pressure gas within the dome.

It will be obvious to those skilled in the art that various other changes may be made in the construction and arrangement without departing from the spirit of the invention and therefore the invention is not limited to what is shown in

the drawings and described in the specification but only as indicated in the appended claims.

I claim:

1. In a water cooler utilizing a refrigerating system of the compressor-condenser-evaporator type driven by an electric motor and having a casing around the motor and compressor connected in the low pressure side of the system, a cooling coil within said casing, and means for 5 circulating waste cooled water through said coil.
2. In a water cooler utilizing a refrigerating system of the compressor-condenser-evaporator type driven by an electric motor and having a casing around the motor and compressor connected in the low pressure side of the system, a 10
- 15

cooling coil within said casing, and means for circulating waste cooled water in heat exchange relation with the incoming water to be cooled and then through said cooling coil.

3. In a water cooler utilizing a refrigerating system of the compressor condenser evaporator type driven by an electric motor and having a casing enclosing and forming a low pressure gas chamber around the motor, a pipe coiled around the top of the casing, and means for circulating 5 waste cooled water in heat exchange relation with incoming water to be cooled and then through said coil of pipe to reduce the temperature of the low pressure gas within said casing.

EDWARD T. WILLIAMS. 15
